UNITED STATES PATENT OFFICE.

THOMAS N. BURGHART, OF PHILADELPHIA, PENNSYLVANIA.

THIEF-TRAP.

1,368,543.

Specification of Letters Patent. Patented Feb. 15, 1921.

Application filed June 26, 1920. Serial No. 392,114.

To all whom it may concern:

Be it known that I, THOMAS N. BURGHART, a citizen of the United States, residing at Philadelphia, in the county of Philadelphia and State of Pennsylvania, have invented certain new and useful Improvements in Thief-Traps, of which the following is a specification.

The main object of my present invention is to prevent the theft of automobiles.

Another object is to provide means for the above purpose which will be operative, when an unauthorized person or thief sits upon the driver's seat of an automobile, to cause a device to be released and automatically operate to grasp and securely hold the legs of the thief to prevent his escape and thus enable the capture of the thief.

Another object is to include an audible alarm which will operate when the automatic device is actuated so as to inform the owner of the automobile or other person that some unauthorized person has attempted to steal the automobile.

Another object is to make the device of my invention of a comparatively simple and durable construction and to provide means to render the device inoperative when the owner of the automobile or other authorized person desires to use the same.

These objects, and other advantageous ends which will be described hereinafter, I attain in the following manner, reference being had to the accompanying drawings in which—

Figure 1 is a sectional elevation of an automobile seat showing my improved device in a position ready to catch a thief if he sits upon the seat.

Fig. 2 is a sectional plan view taken on the line 2—2 of Fig. 1.

Fig. 3 is a view of similar character to Fig. 2 showing the device in the act of operating after a person has sat upon the seat.

Fig. 4 is a view of similar character to Figs. 2 and 3 showing the device having been operated and in a position which it occupies when grasping and holding the legs of a thief.

Fig. 5 is an enlarged fragmentary sectional view showing the pivotal connection of the grasping arms, a spring connection, and a hook for holding the arms against action by the spring,

Fig. 6 is an enlarged fragmentary elevation of certain of the parts shown in Fig. 4, illustrating the grasping arms having been moved into an operative position by the release of the hook, 60

Fig. 7 is a fragmentary plan view taken on the line 7—7 of Fig. 1 and drawn on an enlarged scale,

Fig. 8 is a perspective view showing the arrangement of certain of the alarm elements,

Fig. 9 is a detached perspective view of the grasping arms and the spring for moving the arms together, and

Fig. 10 is a perspective view of the arm connecting yoke which I preferably employ.

Referring to the drawings, 11 represents a seat casing or box which is mounted upon the floor 12 of an automobile and a box 13 having a cylindrical bore is mounted within the casing 11 and secured to the floor 12 by any suitable means such for example as by the screws 13^a. A post 14 has a piston 15 on its lower end which slidably fits within the bore of the box 13. A coiled spring 16 is positioned within the box 13 between the piston 15 and the floor 12 and serves to hold the post 14 in a raised position such as shown in Fig. 1. A seat 17 includes a seat board 18 and a cushion 19. The upper end 75 of the post 14 is secured to the bottom of the seat board 18 and the top of the seat casing 11 is cut away to permit the seat to move downwardly when a person sits thereon and when the device is in a "set" 80 position. The post 14 has a lug 20 thereon having its forward end turned upwardly in the form of a hook adapted to engage under a hook 21 which extends rearwardly from an eyelet 22 formed on the rear end of a grasping arm 23. Another grasping arm 24 has an eyelet 25 at its rear end and a pivot bolt 26 is adapted to extend through the eyelets 22 and 25 to form a pivot connection for the grasping arms 23 and 24. A coiled spring 85 90 95

27 is adapted to be inserted within the eyelets 22 and 25 and has its opposite ends respectively secured to said eyelets and is adapted under operative conditions to move the arms into the position shown in Fig. 4 100 after having been spread into the position shown in Fig. 3 during the operation of the device from its normal position shown in Figs. 1 and 2. A yoke 28 has its arms pivotally mounted on the pivot bolt 26 and forms 105 110

a connection for a strong coiled spring 29; said spring at its forward end being connected to the front board 30 of the seat casing 11. The grasping arms 23 and 24 are 5 preferably made of hollow tempered steel so that while they are of comparatively light weight they are strong and cannot be readily broken. These arms 23 and 24 are curved as shown in Figs. 2, 3, 4 and 9 and have depending pins 31 between their ends which ride in outwardly flared guide rails 32 which are supported in any convenient manner within the space provided by the seat casing 11. In the drawings I have shown for this 10 purpose fixed supporting bars 32a. The front board 30 of the seat casing has two slots 33 out of which the front ends 34 of the grasping arms can be projected; said slots being of sufficient width to permit 15 the arms first to be moved into a wide spring position and afterward moved together for example from the position shown in Fig. 3 into the position shown in Fig. 4.

The spring 29 tends to move arms 23 and 24 forwardly and the torsion spring 27 tends to move the arms together when permitted to do so by the rails 32; it being noted that the forward ends 35 of the rails 32 stop short of the front board 30 and thereby free 30 the grasping arms during their forward movement when the hook 21 is released from the lug 20 which action occurs when a person sits upon the seat 17 and thereby moves the post 14 downwardly against the action 35 of the supporting coiled spring 16; the action being as follows:—

When the device is "set" as shown in Figs. 1 and 2 if a person sits upon the seat 17 the post 14 is lowered and the hook 21 is released from the lug 20 in view of the fact that the lug 20 moves downwardly from under the hook 21. The spring 29 will move the arms forwardly and the outwardly flaring character of the guide rails 32 initially causes the front ends 34 of the grasping arms to be spread and projected outwardly through the slots 33. This action occurs until the pins 31 move out of the front ends 35 of the guide rails 32 and when 45 thus released the torsion spring 27 will act to swing the arms into the position shown in Fig. 4 and thereby grasp the legs of a person who has sat upon the seat and the strength of the spring 27 is such as to prevent the legs of the person from being voluntarily withdrawn from between the grasping arms 23 and 24. The person is thereby held to the seat and cannot get away.

60 The post 14 has a metallic extension 36 which, when lowered during the descent of the post 14, engages between two contact fingers 37 and 38 which are insulated from each other and connected by a wire 39 to a 65 battery or other electric generator 40 which

is in circuit with an electric bell 41 or other suitable electrically operated audible alarm device. Thus when the extension 36 engages between the fingers 37 and 38 an electric circuit is completed through the alarm device 41 so as to produce an audible alarm substantially simultaneous with the grasping action of the arms 23 and 24. 70

As a means for preventing the operation of the device such for example as when the owner or an authorized person desires to use the automobile I provide a bolt 42 which is slidable in bearings 43a; said bolt having a cut away or notched portion 43 which, when slid from under a projection 44 on the post 14, will prevent the post 14 from moving downwardly when a person sits upon the seat 17. In order to prevent tampering with the bolt 42 by an unauthorized person I provide the back board 45 of the seat 85 casing 11 with a door 46 which is locked by a "Corbin", "Yale" or other recognized durable lock 47; this lock being adapted to be opened by a key held by the owner of the automobile or other authorized person. 90 Thus access to the bolt 42 is only permitted to the proper person and when the device is in a "set" position the notched portion 43 is moved under the projection 44 so as to permit the descent of the post 14 when a 95 person sits upon the seat 17.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended 105 claims.

Having thus described my invention, what I claim as new and desire to secure by Letters Patent is:—

1. The combination of a depressive seat 110 and means automatically operative upon the depression of the seat for grasping and securely holding the legs of a person sitting upon the seat; substantially as described.

2. The combination of a seat casing; a 115 seat above said casing; grasping arms within said casing; means for engagement with said seat and adapted to normally hold said grasping arms within the casing; and means automatically operative when said seat-engaging means is operated due to a person sitting upon the seat to release said arms and permit said automatic means to move said arms into a position out of the casing to grasp and hold the legs of a person sitting upon said seat; substantially as described.

3. A device of the character described including a seat casing; a seat mounted above said casing; a post depending from said 130

- seat into the casing; a spring for holding said seat in a raised position; grasping arms mounted within said seat casing and having a portion for engagement with the part 5 on said post for normally holding said arms in the casing; and means automatically operative when said arms are released from said post due to the downward movement thereof by a person sitting upon said seat 10 to cause said arms to be projected out of the casing and moved into a position to grasp the legs of a person sitting upon said seat; substantially as described.
4. A device of the character described including a seat casing; a seat mounted above said casing; a post depending from said seat into the casing; a spring for holding said seat in a raised position; grasping arms mounted within said seat casing and having 15 a portion for engagement with a part on said post for normally holding said arms in the casing; guiding means for said arms; and means automatically operative when said arms are released from said post due to 20 the downward movement thereof by a person sitting upon said seat to cause said arms to be projected out of the casing and moved into a position to grasp the legs of a person sitting upon said seat, said guiding means 25 having portions adapted to initially spread said arms during their outward movement and then permit them to swing toward each other; substantially as described.
5. A device of the character described including a seat casing; a seat mounted above said casing; a post secured to said seat and depending into the casing; a spring for holding said seat in a raised position; a hooked lug projecting from said post; arms 30 pivotally connected together and having a hook for engagement over and in back of said hooked lug; and means automatically operative to move the forward ends of said arms out of said casing and toward each 35 other when said post is moved downwardly by a person sitting upon said seat to cause the forward end portions of said arms to grasp and hold the legs of a person sitting upon said seat; substantially as described.
6. A device of the character described including a seat casing; a seat mounted above said casing; a post secured to said seat and depending into the casing; a spring for holding said seat in a raised position; a hooked lug projecting from said post; arms 40 pivotally connected together and having a hook for engagement over and in back of said hooked lug; guiding means having outwardly flared portions, said arms having 45 portions normally confined to said guiding means; and means automatically operative to move the forward ends of said arms out of said casing and toward each other when said post is moved downwardly by a person 50 sitting upon said seat to cause the forward
- end portions of said arms to grasp and hold the legs of a person sitting upon said seat, said flared portions of the guiding means serving to initially spread the forward ends of said arms prior to their movement toward 55 each other whereby a wide spread is imparted to said outer ends of the arms to increase their grasping scope; substantially as described.
7. The combination of a depressive seat 75 and means automatically operative upon the depression of the seat for grasping and securely holding the legs of a person sitting upon the seat; and means for rendering the action of said automatic means inoperative; 80 substantially as described.
8. The combination of a seat casing; a seat above said casing; grasping arms within said casing; means for engagement with said seat and adapted to normally hold said grasping 85 arms within the casing; means automatically operative when said seat-engaging means is operated due to a person sitting upon the seat to release said arms and permit said automatic means to move said arms into a 90 position out of the casing to grasp and hold the legs of a person sitting upon said seat; and means co-acting with said seat-engaging means during its movement to effect the 95 operation of an audible alarm; substantially as described.
9. The combination of a seat casing; a seat above said casing; grasping arms within said casing; means for engagement with said seat and adapted to normally hold said 100 grasping arms within the casing; means automatically operative when said seat-engaging means is operated due to a person sitting upon the seat to release said arms and permit said automatic means to move said arms into a position out of the casing 105 to grasp and hold the legs of a person sitting upon said seat; an electrically operative audible alarm device having a normally open circuit; and means co-operative with 110 said seat-engaging means during the movement of the latter to close said circuit and produce an alarm; substantially as described.
10. A device of the character described including a seat casing; a seat mounted above said casing; a post depending from said seat into the casing; a spring for holding said seat in a raised position; grasping 115 arms mounted within said seat casing and having a portion for engagement with the part on said post for normally holding said arms in the casing; means automatically operative when said arms are released from said post due to the downward movement 120 thereof by a person sitting upon said seat to cause said arms to be projected out of the casing and moved into a position to grasp the legs of a person sitting upon said seat, said post having a projection; and a bolt 125 130

confined within said casing and having a cut-away portion movable into and out of the path of movement of said projection whereby the device is rendered selectively operative or inoperative; substantially as described.

In testimony whereof I have signed my

name to this specification in the presence of two subscribing witnesses.

THOMAS N. BURGHART.
